CLAIM

The ornamental design for a composite delivery system, as shown and described.

DESCRIPTION

FIG. 1 is an upper perspective view of a composite delivery system;

FIG. 2 is a left-side view of the composite delivery system;

FIG. 3 is a right-side view of the composite delivery system;

FIG. 4 is a front view of the composite delivery system;

FIG. 5 is a rear view of the composite delivery system;

FIG. 6 is a top view of the composite delivery system; and,

FIG. 7 is a bottom view of the composite delivery system.

The broken lines showing portions of the composite delivery system are included for the purpose of illustrating environmental structures and form no part of the claimed design.

1 Claim, 4 Drawing Sheets
